DESIGN FOR A KNEE DESK

Harley P. Leatherman, St. Petersburg, Fla.

Application February 2, 1944, Serial No. 112,419

Term of patent 7 years

(Cl. D33—7)

To all whom it may concern:

Be it known that I, Harley P. Leatherman, a citizen of the United States, residing at St. Petersburg, in the county of Pinellas and State of Florida, have invented a new, original, and ornamental Design for Knee Desks, of which the following is a specification, reference being had to the accompanying drawings, forming part thereof.

Fig. 1 is a top plan view of a knee desk,

Fig. 2 is a bottom plan view of a knee desk showing my supporting leg folded to the bottom surface thereof.

Fig. 3 is a front edge elevational view showing the supporting leg, lateral to the knee desk top, and in position for use.

Fig. 4 is a side elevational view thereof, as positioned in Fig. 3.

The essential feature of the knee desk disclosed resides in the configuration of the supporting leg thereof.

What is claimed is:

The ornamental design for a knee desk, as shown and described.

HARLEY P. LEATHERMAN.
